UNITED STATES PATENT OFFICE.

GEORGE W. MORSE AND THEODORE W. PLUMB, OF PITTSBURG, PENNSYLVANIA, ASSIGNORS, BY MESNE ASSIGNMENTS, TO THE PARISH & BINGHAM COMPANY, OF CLEVELAND, OHIO, A CORPORATION OF WEST VIRGINIA.

WHEEL.

SPECIFICATION forming part of Letters Patent No. 784,958, dated March 14, 1905.

Application filed July 1, 1903. Serial No. 163,862.

To all whom it may concern:

Be it known that we, GEORGE W. MORSE and THEODORE W. PLUMB, residents of Pittsburg, in the county of Allegheny and State of Pennsylvania, have invented a new and useful Improvement in Wheels; and we do hereby declare the following to be a full, clear, and exact description thereof.

Our invention relates to wheels for vehicles, and has special reference to the hubs employed on vehicles.

The object of our invention is to provide a wheel in which all of the hub and its connecting parts are formed of cold-rolled stamped metal, preferably steel, and one which is cheap, strong, and simple in its construction.

Our invention consists, generally stated, in the novel arrangement, construction, and combination of parts, as hereinafter more specifically set forth and described, and particularly pointed out in the claims.

To enable others skilled in the art to which our invention appertains to construct and use our improved wheel, we will describe the same more fully, referring to the accompanying drawings, in which—

Figure 1 is a longitudinal central section of a hub constructed in accordance with our invention. Fig. 2 is an inner face view of the same. Fig. 3 is a cross-section on the line 3-3, Fig. 1. Fig. 4 is a side view of the spoke, showing the same partly in section. Fig. 5 is a sectional view showing another form of holding the disk or cap-plate.

Like symbols of reference herein indicate like parts in each of the figures of the drawings.

As illustrated in the drawings, 1 represents the hub, which consists of the barrel 2 for fitting around the axle (not shown) and formed of stamped cold-rolled metal, preferably steel. The outer end 3 of the barrel 2 is provided with the threaded portion 4 on the exterior face 5 of said barrel, and such threaded portion is countersunk or formed within such face 5, so that the outer ends of the threads forming such threaded portion 4 will be flush with the said face of the barrel. A cap 6, hav-

ing an interiorly-threaded portion 7 therein, is adapted to fit over and engage the threaded portion 4 on said barrel 2 by its threaded portion 7 for closing the outer end 3 of said barrel. The opposite or inner end 3' of said barrel 2 is provided with an annular flange or shoulder 8 on the exterior face 5 of said barrel, and against said shoulder fits the disk or cap-plate 9, which is formed of cold-rolled metal, preferably steel. This cap-plate 9 is provided with the circular central opening 10 therein, and such opening is threaded, as at 11, 50 for engaging with a raised threaded portion 12, formed on the end 3' of the exterior face 5 on the barrel 2, and such cap-plate 9 after being screwed up to place against said shoulder 8 is held in place in a seat 14 by means of the bent 55 flanged portion 13, formed on the said end 3' of said barrel and engaging with the outer face 9' of said cap-plate 9. A raised threaded portion 16 is formed on the exterior face 5 of said barrel 2, and between said threaded 60 portion 16 and the shoulder 8 is the unthreaded or smooth portion 17, which is flush with the outer ends of the threads forming the threaded portion 16 and within which is secured the tongue or feather 18. Another disk or cap-plate 19, formed of stamped cold-rolled metal, 65 preferably steel, fits around the face 5 of said barrel 2 and is provided with a collar or sleeve 20, which is formed as part of said plate and extends out from the outer face 19' thereof. 70 The sleeve 20 fits over the smooth portion 17 and is provided with a groove 21 on its smooth interior face 22, forming the central opening thereof for fitting over the feather 18 in said portion 17. A nut 23 is adapted to engage 75 by its threaded interior face 24 with the raised threaded portion 16 on the exterior face 5 of the barrel 2 and be screwed up against the end of said sleeve 20 for holding said cap-plate 19 in place on the smooth portion 17. 80 The two cap-plates 9 and 19 are adapted to form an annular tapered space or seat 25 between them on the smooth portion 17, and the inner faces 9" and 19" of said plates 9 and 19 are inclined or flared inwardly, as at 25', from 85 the central openings 10 and 22, respectively, 90

95

thereof. Fitting within the annular tapered seat 25 are the tubular spokes 26, which are formed of stamped cold-rolled metal, preferably steel, and the hollow bases 27 of these spokes 26 are made of wedge form, as at 28, so that each spoke will resemble and form a keystone, like in an arch, which will lock or bind one another. The flared end walls 29, formed by these keystones on the hollow bases 27 of the spokes 26, are placed side by side and against each other continuously around the barrel 2 within the tapered seat 25 formed by the plates 9 and 19, and the base end 30 of each spoke is made broader, as at 30', so as to form the flared side walls 31 thereon, which fit against and conform to the flared inner faces 25' on the plates 9 and 19 forming said seat 25. The base end 30 of each of the spokes 26 is also open, as at 32, so as to communicate with the interior of the hollow bases 27, and the end faces of said bases 27 are formed on a curved line, as at 33, so as to form segments of a circle which will fit against and correspond to the smooth portion 17 on the barrel 2. The spokes 26 are further and more securely held in place by means of the bolts 34, which preferably connect every alternate spoke with the plates 9 and 19, and such bolts pass through holes 35 in the plates 9 and 19 and through like holes 35' in the flared side walls 31 of the hollow bases 27, while a nut 34' is adapted to engage with the ends of each of said bolts 34 to hold them in place.

The manner of assembling our improved wheel is as follows: The barrel 2 is made to finished shape by forming the threaded portions 4, 12, and 16 and the shoulder 8 on the exterior face thereof, which barrel also is formed with the smooth portion 17 between said shoulder 8 and the threaded portion 16, and during the formation of said barrel 2 the annular lip extension 36 is formed on the inner end 3' of the barrel beyond the threaded portion 12, which is provided with the rounded inner end 37. After the said barrel 2 is thus finished the cap-plate 9 is placed over the lip extension 36 on the inner end 3' of said barrel and screwed to place against the shoulder 8 on said barrel by means of the central opening 10 of said plate engaging with the threaded portion 12 on the barrel by its screw-threads 11. After this is accomplished the barrel 2, carrying such plate 9, is held in any suitable manner, and the lip or extension 36 on the inner end 3' of said barrel is upset or bent in any suitable manner to form the flanged portion 13, and such portion 13 is compressed against the outer face 9' of said plate to hold the same tightly and secured against said shoulder 8 on the threaded portion 12 and within the seat 14 formed by said shoulder and portion 13. The outer cap-plate 19 is then placed on said barrel 2 by passing the same over the outer end 3 thereof and is set in position on the smooth portion 17 of said barrel, being

held and prevented from turning by the feather 18 in the barrel fitting within the groove 21 in the sleeve 20 of said plate. The parts can then be held and the spokes 26 placed within the space or seat 25 between the plates 9 and 19, with the curved bottom faces 33 on the base ends 30 of said spokes fitting against and conforming to the smooth portion 17 on the barrel 2, and after this is done bolts 34 are passed through the holes 35 in the plates 9 and 19 and through the holes 35' in the flared side walls 31 of the hollow bases 27 on said spokes 26. The cap-plate 9 can now be held against the hollow bases 27 of said spokes by any suitable compression means, and while so held the nut 23, having been passed over the end 3 of the barrel 2, is screwed tightly to place against the end of the sleeve 20 on the plate 19 by means of its threaded interior face 24 engaging with the raised threaded portion 16 on the said barrel. The nuts 34' are then screwed onto the ends of each of the bolts 34 and up tightly against the outer face 19' of said plate 19 while the said plate is so held by compression, when the hub A is then ready for the connecting up of the spokes 26 to the rim (not shown) and the placing of the cap 6 on the outer end 3 to form the wheel.

If desired, the threaded portion 12 on the outer end 3' of the barrel 2 can be dispensed with and the lip or extension 36 beyond the shoulder 8 be made plain or smooth throughout its length on the exterior face 5, as at 12', so that the cap-plate 9 can fit over said smooth portion 12' against the shoulder 8 and the extension 36 upset or bent against the said plate to form the flanged portion 13 and hold the plate in place within the seat 8' formed by the shoulder 8 and flanged portion 13.

Various modifications and changes in the construction and design of the hub may be resorted to without departing from the spirit of the invention or sacrificing any of its advantages.

It will thus be seen that our improved hub for wheels gives a broad substantial base by the bases of the spokes resting around the barrel, and being formed wedge shape on all sides of such bases enables the spokes to be held firmly and securely in place and will prevent any tendency of the wheel to dish. The wheel with such hub can be made light in weight without impairing its strength, and there is no liability of the parts becoming loose in usage, while such parts are made light, firm, and durable, are not subjected to any wear and do not require separating when once assembled.

What we claim as our invention, and desire to secure by Letters Patent, is—

1. A metallic hub, comprising a barrel having a shoulder thereon, disks secured on said barrel adapted to form an annular space between them around said barrel and one of said disks being adapted to fit against said shoulder, 130

spokes secured within said space, and a lip on said barrel adapted to form a seat for the disk fitting against said shoulder and be compressed against the said disk to hold the same 5 in place.

2. A metallic hub, comprising a barrel having a shoulder thereon, disks secured on said barrel adapted to form an annular space between them around said barrel and one of 10 said disks being adapted to fit against said shoulder, spokes secured within said space, and a lip on the end of said barrel adapted to be bent against said disk to form a flanged portion, said flanged portion being adapted 15 to form a seat for said disk and being compressed against said disk to hold it in place within said seat and against the shoulder.

3. A metallic hub, comprising a barrel having a shoulder thereon and provided with a 20 threaded portion adjacent to said shoulder, disks secured on said barrel adapted to form an annular space between them around said barrel and one of said disks being adapted to engage said threaded portion and fit against 25 said shoulder, and a lip on the end of said barrel adapted to be bent against said disk to form a flanged portion, said flanged portion being adapted to form a seat for said disk and being compressed against said disk to hold it 30 in place within said seat and on said threaded portion against the shoulder.

4. A metallic hub, comprising a barrel having a shoulder thereon, disks secured on said barrel adapted to form an annular space between them around said barrel and one of said 35 disks being adapted to fit against said shoulder, spokes secured within said space, and a lip on the end of said barrel adapted to be bent against said disk to form a flanged portion, said 40 lip having a curved inner end to form a rounded outer end on said flanged portion and such flanged portion being adapted to form a seat for said disk and be compressed against said disk to hold it in place within said seat and 45 against said shoulder.

5. A metallic hub, comprising a barrel having a shoulder thereon, disks secured on said barrel adapted to form an annular space between them around said barrel and one of said 50 disks being adapted to fit against said shoulder, a lip on said barrel adapted to form a seat for the disk fitting against the shoulder and be

compressed against the said disk to hold the same in place, said disks having their inner faces inwardly flaring from said barrel to form 55 wedge-shaped faces for said space, and tubular spokes having hollow base ends secured within said space and having their side faces outwardly flaring to engage with the flared inner faces on said disks, said hollow base ends also 60 having their end faces inwardly flaring to fit against each other around the barrel and being provided with curved open bottom faces to conform to the shape of said barrel.

6. A metallic hub, comprising a barrel having a threaded portion thereon and a smooth portion adjacent thereto, disks secured in said barrel adapted to form an annular space between them around said barrel, tubular spokes secured within said space, a lug or feather on 65 said smooth portion, a sleeve on one of said disks having a groove therein adapted to engage with said feather, and a nut adapted to engage with the threaded portion on said barrel and be screwed up against the end of said 70 sleeve to hold the disk carrying said sleeve and the spokes in place.

7. A metallic hub, comprising a barrel having a threaded portion thereon and a smooth portion adjacent thereto, disks secured on said barrel adapted to form an annular space between them around said barrel, tubular spokes secured within said space, bolts having nuts thereon passing through said disks and spokes, a lug or feather on said smooth portion, a 80 sleeve on one of said disks having a groove therein adapted to engage with said feather, and a nut adapted to engage with the threaded portion on said barrel and be screwed up against the end of said sleeve to hold the disk 85 carrying said sleeve and the spokes in place, said disk being held by pressure against said spokes while said nut is being screwed up against said sleeve and while the nuts are 90 screwed up on the said bolts.

In testimony whereof we, the said GEORGE W. MORSE and THEODORE W. PLUMB, have hereunto set our own hands.

GEORGE W. MORSE.
THEODORE W. PLUMB.
